UNITED STATES PATENT OFFICE.

JAMES A. HORTON, OF READING, MASSACHUSETTS.

POWER-PRESS.

SPECIFICATION forming part of Letters Patent No. 361,158, dated April 12, 1887.

Application filed July 15, 1886. Serial No. 208,105. (No model.)

To all whom it may concern:

Be it known that I, JAMES A. HORTON, of Reading, in the county of Middlesex and State of Massachusetts, have invented certain new and useful Improvements in Power-Presses, of which the following is a specification.

My invention relates to power-presses, and has for its object to provide improved means for adjusting the bed vertically, whereby it can be raised or lowered with certainty and great nicety to any degree or extent, and effectively secured in any position to which it may be adjusted.

The invention also has for its object to improve the means whereby the plunger is raised and lowered.

To the foregoing ends the invention consists in the improvements which I will now proceed to describe and claim, so that others skilled in the art may be able to make and use the same, the accompanying drawings forming a part of this specification, and the invention being set forth with distinctness and particularity at the end of the description of the construction and operation of the machine.

Of the drawings, Figure 1 represents a side elevation of the entire machine. Fig. 2 is a vertical section through the upper portion thereof. Fig. 3 is a cross-section on the line $x-x$ of Fig. 1, looking down upon the bed of the machine. Fig. 4 is a sectional detail view on the line $y-y$, Fig. 1.

Similar letters of reference indicate similar parts in all of the figures.

In the drawings, a represents the frame of the machine, consisting of a substantial pillar or post adapted to support the various parts of the contrivance.

b represents the bed, constructed to be guided in its vertical movements in a guideway, V-shaped in horizontal cross-section, (see Fig. 3,) formed in the frame, and to be supported therein by means of a rod, c , sustained vertically in the machine and having a screw-threaded connection with the bed, as shown in Fig. 2, and by rods or bolts d , passing horizontally through vertical slots e , formed in the sides of the V-shaped guideway and at the vertex thereof in the frame. Said bolts d have also a screw-threaded connection with the bed, and their outer ends, f , are headed and adapted to have a key or crank

applied thereto, and be turned up so as to effectually clamp or lock the bed in any position to which it may be adjusted by means of the vertical rod c .

The upper end of rod c extends through a portion of the frame into an opening, g , formed therein, where said rod is provided with a bevel-gear, h , rigidly secured thereto, the lower face of which rests upon the floor of the opening g . A bracket, i , is secured to the side of the frame near opening g , to the outer end of which is secured a stud, j , forming a journal for a bevel-gear, k , constructed and arranged to mesh with bevel-gear h on the upper end of rod c . Gear-wheel k is rigidly secured to its stud j , and the latter is adapted to be turned in its bearings in the bracket i .

The outer end of stud j , like the outer ends of rods d , is squared, so as to have a key or crank, l , applied thereto for the purpose of revolving gear k , which in turn revolves gear h on shaft or rod c , whereby, when the bed is free from the clamping influence of rods d , it may be raised or lowered, as will be understood without further description.

When the bed is adjusted in proper position in the manner described, which adjustment can be made with the utmost nicety, the key or crank l may be removed from stud j and applied to the square heads f of rods d , and the latter turned up so as to clamp the bed securely in position in its guideway on the frame a . The rods or bolts d , being arranged at the sides of the V-shaped guideway and at the vertex thereof, provide a construction by which the bed can be clamped very firmly in position, and constitute an important feature of my invention.

m represents the main shaft, supported in a bearing formed in the frame, to the rear end of which shaft the driving-pulley n is secured in any suitable way. The forward portion of shaft m is turned down, so as to leave a pin, o , thereon at a point eccentric with the axis of rotation of the shaft. A portion of the shaft m on its extreme forward end is left undisturbed, so as to practically form a disk, p , on the forward end of pin o , making the shaft m , pin o , and disk p integral parts of each other, so that they cannot readily become loosened or displaced by the operation of the pitman. q represents the plunger, which is adapted

to be moved and guided in ways formed in the frame *a* above the bed *b*. The plunger is counterbored in its upper portion, as represented in Figs. 2 and 4 and in dotted lines in Fig. 1, 5 to receive a portion of the lower rounded head or end, *r*, of pitman *s*, a journal-box, *t*, being formed on the upper end of the pitman, which journal-box is adapted to be secured to journal-pin *o*, so that the latter may turn therein 10 in any suitable or well-known way.

A cap, *u*, counterbored so as to receive the portion of the lower rounded end of pitman *s*, (not inclosed in the counterbore formed in the plunger,) is constructed to fit over said 15 lower end of the pitman and to be secured to the plunger by means of dowel-pins *v*, formed on or secured in the cap and fitting into suitable holes formed in the plunger, as represented in Fig. 4. A bolt, *w*, passes through 20 the cap, the lower end of the pitman, and the side of the bed, and is secured to the latter, the construction and arrangement being such that the pitman may turn freely on said bolt and the latter have a nut screwed on its outer 25 forward end, by which the cap, with its dowel-pins, may be held securely in place on the plunger. A short slot, *y*, is formed in the upper part of the inclosure constituted by the counterbores in the plunger and the cap *u*, which 30 permits the shaft of the pitman *s* to play therein in the operation of the press.

The construction described is designed to secure strength in the several parts and steadiness and exactness of motion in the operation 35 of the press, as well as simplicity in their form and arrangement.

In the revolution of shaft *m*, journal-pin *o*, operating as an eccentric or crank on the upper end of pitman *s*, will through the latter 40 vice raise and lower plunger *q*, the lifting of the latter being effected by the operation of rounded head *r* on plunger *q* and cap *u* in the described counterbores in which it is fitted, and the pressure on the plunger is effected by the 45 pressure of the lower end of the pitman thereon, as will be understood. By this construction pin *w* is practically relieved of all strain, excepting such as is required to keep the cap *u* in place.

50 The guideway for the bed formed in the frame is preferably of triangular or **V** form, and the adjacent portion of the bed is of corresponding form, as represented in Fig. 3, this construction being designed to take up the wear 55 of the parts and secure a close junction or wedging fit thereof, and consequently the secure clamping together of the same.

The full and dotted lines in Fig. 1, representing the bed and its adjuncts, show the extent to which the bed may be adjusted.

What I claim is—

1. In a power-press, the frame provided with a guideway **V**-shaped in horizontal cross-section, the adjustable bed having a form in that part adjacent to the **V**-shaped guideway corresponding in shape to the latter, and screw bolts or rods for clamping the bed in the guideway of the frame, all constructed, arranged, and combined as and for the purposes hereinbefore set forth. 65

70 2. In a power-press, the frame provided with a guideway **V**-shaped in horizontal cross-section, slots *e* formed in the sides and at the vertex of said **V**-shaped guideway, the adjustable bed having a form in that part adjacent to the **V**-shaped guideway corresponding in shape to the latter, and bolts *d*, passing through said slots *e* and screw-tapped into the bed for clamping the latter in its guideway, all combined, arranged, and operating as and for the 80 purposes hereinbefore set forth.

75 3. The combination, with the frame and guideway formed therein, of the bed, the revolute rod *c*, supported in the frame and having a screw-threaded connection with the bed, 85 and mechanism, substantially as set forth, for clamping the bed to the frame, as set forth.

4. The combination, with the frame, of the bed, the rod *c*, supported in the frame and having a screw-threaded connection with the bed, 90 bevel-gear *h*, bracket *i*, journal-stud *j*, bevel-gear *k*, and crank or key *l*, as set forth.

5. The combination of the frame provided with the slots *e*, bed *b*, rod *c*, bevel-gear *h*, bracket *i*, journal-stud *j*, bevel-gear *k*, rods *d*, 95 and crank or key *l*, as set forth.

6. The pitman provided with a rounded enlargement on one end, the plunger, counterbored as described, a cap, also counterbored, said counterbores in the plunger and cap being of a form adapted to fit the enlarged rounded end of the pitman, and a clamping-bolt, all arranged, combined, and operating as and for the purposes set forth. 100

7. The pitman provided with the rounded 105 head or end *r*, the plunger, counterbored as described, the cap, also counterbored and provided with the dowel-pins *v*, and the clamping-bolt *w*, all combined, arranged, and operating substantially as and for the purposes set 110 forth.

In testimony whereof I have signed my name to this specification, in the presence of two subscribing witnesses, this 1st day of July, 1886.

JAMES A. HORTON.
